UNITED STATES PATENT OFFICE

114,901

DESIGN FOR A CYLINDER-HEAD PULLER

Floyd L. Niles, Oneida, N. Y.

Application August 18, 1938, Serial No. 79,430

Term of patent 3½ years

To all whom it may concern:

Be it known that I, Floyd L. Niles, a citizen of the United States of America, residing at Oneida, in the county of Madison and State of New York, have invented a new, original, and ornamental Design for a Cylinder-Head Puller, of which the following is a specification, reference being had to the accompanying drawing, forming part thereof, in which:

Figure 1 is a front perspective view of the cylinder-head puller showing my design.

Figures 2 and 3 are front side elevational and inverted plan views, respectively, of the cylinder-head puller shown in Figure 1.

Figure 4 is a transverse sectional view taken substantially on line 4—4, Figure 2.

I claim:

The ornamental design for a cylinder-head puller, as shown.

FLOYD L. NILES.
